UNITED STATES PATENT OFFICE.

HERBERT Q. GUTH, OF ELGIN, ILLINOIS, ASSIGNOR TO POSTL, INC., OF CHICAGO,
ILLINOIS, A CORPORATION OF ILLINOIS.

EXERCISER.

Application filed July 20, 1925. Serial No. 44,779.

My invention relates to that general class of devices known as exercisers and has among its other objects the production of devices of the kind described which are convenient, compact and satisfactory for use wherever found applicable.

In one form of the invention two relatively movable handle members are yieldingly urged by springs out of a position wherein 10 a shouldered disc carried by one member will engage a seat formed on the other. The handle members may be brought into said position by grasping them with one's hands and then displacing the members relatively to 15 each other against the action of the springs. Means is provided for adjusting the members in accordance with the strength of the user.

Many other objects and advantages of the 20 construction herein shown and described will be obvious to those skilled in the art from the disclosure herein given.

To this end my invention consists in the 25 novel construction, arrangement and combination of parts herein shown and described, and more particularly pointed out in the claims.

In the drawings, wherein like reference 30 characters indicate like or corresponding parts;

Fig. 1 is a perspective view of an exerciser embodying the invention;

Fig. 2 is a longitudinal central section taken through my improved exerciser;

Figs. 3, 4 and 5 are sections taken on lines 35 3—3, 4—4, 5—5, respectively, of Fig. 2; and

Fig. 6 is a fragmentary section taken 40 through an exerciser embodying another form of the invention, the section being taken on a line corresponding to the line on which Fig. 2 is taken.

Referring for the present to Figs. 1 to 5, inclusive, the reference characters 10 and 11 designate in general two handle members, which comprise knurled tubes 12 and 13, respectively. One end of the tube 12 is closed by a cap 15 and an extension 16 projects from the other end thereof, the extension 16 being secured to the tube 12 by a pin 17. A notch 19 formed in the extension 16 intermediate its ends accommodates the free end of a bracket 21 which is rigidly secured to one end of the tube 13, the other end of the tube 13 being closed by a collar 23 which is 55 rigidly secured in place in the tube in any

suitable manner. Rotatably mounted in the collar 23 is a pin 24 provided with a knurled head 25. Rigidly secured to the inner end of the pin 24 is a tubular member 27 provided with external screw-threads 28. Threaded 60 upon the tubular member 27 is a washer 30. The washer 30 is prevented from rotating around the longitudinal axis of the tubular member 27 by a pin 31 which projects through an aperture 32 formed in the washer, the pin 31 being rigidly secured to the collar 23. Mounted in the tubular member 27 and projecting therefrom is a helical compression spring 34, the upper end of which is of reduced diameter, as at 35. Secured to the spring 34 at the point where it is reduced in diameter is a disc 37 which is free to move longitudinally in the tube 13. To secure the disc 37 to the spring 34 I preferably provide it with a central aperture 38 75 through which the reduced portion 35 of the spring may be forced until the disc seats itself against a shoulder formed by that portion of the spring which is of larger diameter. Disposed in the tube 13 and interposed between the washer 30 and the disc 37 is a helical compression spring 40, which is of larger diameter than the spring 34 and is preferably made of heavier wire.

The free end of the reduced portion 35 85 of the spring 34 preferably engages a conical depression 42 formed in one end of a pin 43 which projects from the aforementioned extension 16. Slidably mounted upon the pin 43 is a disc 44 which is provided with an annular shoulder 45 adapted to seat upon the open end of the tube 13. Disposed around the pin 43 and interposed between the disc 44 and the extension 16 is a compression spring 47 which yieldingly holds 95 the annular shoulder 45 in engagement with the open end of the tube 13 when the handle member 12 is in the position wherein it is shown in full lines in Fig. 2. Projecting from the disc 44 and disposed around the compression spring 47 is a sleeve 48 which 100 protects the spring from injury.

The pin 43 is formed with a conical end 50 movably seated in a conical depression 51 formed in the free end of the bracket 21. 105 Mounted in the free end of the bracket 21 is a pin 52 having a conical part 53 which seats in a conical depression 54 formed in the extension 16. It will be noted that the longitudinal axes of the tube 13, the disc 44, 110

the pin 43, the pin 52 and the tube 12 are substantially coincident when the handle members 10 and 11 are in the relative positions wherein they are shown in full lines in Fig. 2.

When the improved device is to be used, the disc 44 is first unseated from the open end of the tube 13 by raising it against the action of the spring 47, whereupon the spring 34 and 40 cooperate to tilt the handle member 10 to a position such as illustrated in dotted lines in Fig. 2. The springs 34 and 40 will then resist any force tending to return the handle member 10 to the position wherein it is shown in full lines in Fig. 2. To return the handle member 10 to said full line position, one may grasp the member 10 and 11 in one's hands and then displace them relative to each other against the action of the springs 34 and 40 until the longitudinal axis of the tube 12 will coincide with the longitudinal axis of the tube 13, whereupon the spring 47 will extend itself to seat the disc 44 upon the open end of the tube 13. In practice the springs 34 and 40 are so designed that it requires considerable strength to bring the handle member 10 into the position wherein the disc 44 may seat upon the tube 13. The device may be adjusted to meet the strength of the user. Thus, if the knurled nut 25 is revolved in one direction, the washer 30 will move away from the disc 37 and permit the spring 40 to lengthen itself. It will then require less force to seat the disc 44 upon the open end of the tube 13. If the knurled nut 25 is revolved in the opposite direction, the washer 30 will approach the disc 37 and compress the spring 40 whereupon it will require a greater force to seat the disc 44 upon the tube 13. In Fig. 6 I have shown another form of the invention wherein the disc 37 of Figs. 1 to 5, inclusive, is omitted. A compression spring 40^a is used in place of the aforementioned compression spring 40, the compression spring 40^a having one of its ends secured in any suitable manner to one end of a spring 34^a replacing the aforementioned spring 34. The spring 40^a may be secured to the spring 34^a by twisting some of the turns of the spring 40^a tightly around several of the turns of the spring 34^a. The remaining construction in the modified form is substantially identical with the construction illustrated in Figs. 1 to 5, inclusive, and need not be shown or described. Obviously, the form of the invention which is shown in Fig. 6 may be used in substantially the same manner as that form which is illustrated in Figs. 1 to 5, inclusive.

Having thus described my invention, it is obvious that various immaterial modifications may be made in the same without departing from the spirit of my invention;

hence I do not wish to be understood as limiting myself to the exact form, construction, arrangement and combination of parts herein shown and described or uses mentioned.

What I claim as new and desire to secure by Letters Patent is:

1. A device of the class described comprising a pair of pivotally connected normally aligned handle members, an element carried by one of the members adapted to lock said members against relative movement when in axial alignment, and a compression spring carried by said member adapted to yieldingly hold said element in its position of locking engagement and to yieldingly hold said members out of alignment when said element is removed from its position of locking engagement.

2. A device of the class described comprising a pair of pivotally connected normally aligned handle members, an element carried by one of the members adapted to lock said members against relative movement when in axial alignment, and a compression spring carried by said member adapted to yieldingly hold said element in its position of locking engagement and to yieldingly hold said members out of alignment when said element is removed from its position of locking engagement, and a second compression spring axially mounted on the other normal member also adapted to yieldingly force and hold said members out of their position of axial alignment when said element is removed from the position of locking engagement.

3. A device of the class described comprising a pair of normally aligned handle members, a bracket secured to one of said members and provided with means for movably mounting the other member thereon, and a spring carried by one of said members adapted to yieldingly hold said members out of alignment.

4. A device of the class described comprising a pair of normally aligned handle members, a bracket rigidly secured to one of the members and provided with means for movably holding the other member, an element carried by one of said members adapted to lock said member against relative movement when in axial alignment, and a compression spring carried by said element carrying member adapted to yieldingly hold said element in its position of locking engagement and to yieldingly hold said members out of alignment when said element is removed from its position of locking engagement.

5. A device of the class described comprising a pair of pivotally connected normally aligned handle members, a bracket rigidly secured to one of said members for pivotally connecting the other member there-

to, an element carried by one of the members adapted to lock said members against relative movement when in axial alignment, and a compression spring carried by said member adapted to yieldingly hold said element in its position of locking engagement and to yieldingly hold said members out of alignment when said element is removed from its position of locking engagement, and a second compression spring

axially mounted on the other normal member also adapted to yieldingly force and hold said members out of their position of axial alignment when said element is removed from the position of locking engagement. 15

In testimony whereof, I have hereunto signed my name.

HERBERT Q. GUTH.
